UNITED STATES PATENT OFFICE.

EDWIN CARLSON, OF MINNEAPOLIS, MINNESOTA.

ENTER LOCK FOR ELEVATORS.

Application filed August 30, 1922. Serial No. 585,297.

To all whom it may concern:

Be it known that I, EDWIN CARLSON, a citizen of the United States, residing at Minneapolis, in the county of Hennepin and State of Minnesota, have invented certain new and useful Improvements in "Enter Locks" for Elevators; and I do hereby declare the following to be a full, clear, and exact description of the invention, such as will enable others skilled in the art to which it appertains to make and use the same.

My present invention has for its object to provide an extremely simple and highly efficient "enter lock" for elevators, and which "enter lock" is of the type whereby the power-controlling means for the elevator car is mechanically and automatically locked when said car is at rest with its floor level with the building floor or within a predetermined distance above or below the same, and for mechanically and automatically locking the elevator shaft closure gate closed and for releasing the same by a movement of said power-controlling means to neutral position.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary view, with some parts sectioned, showing a car for a hydraulic elevator, the floor of a building and a shaft closure gate, the gate being closed;

Fig. 2 is a view partly in elevation and partly in vertical section taken on the line 2—2 of Fig. 1;

Fig. 3 is a view corresponding to Fig. 1 but showing different means for controlling the operating lever when in neutral position.

Fig. 4 is a view partly in plan and partly in horizontal section taken on the line 4—4 of Fig. 3.

Fig. 5 is a view corresponding to Fig. 1

with the exception that the car is for an electric elevator;

Fig. 6 is a view partly in elevation and partly in vertical section taken on the line 6—6 of Fig. 5; and

Fig. 7 is a view in diagram showing a switch and controlling means for the car illustrated in Fig. 5.

Referring first to the invention illustrated in Figs. 1 and 2, the numeral 8 indicates the car of a hydraulic elevator arranged to travel in an elevator shaft 9 which extends through a building floor 10, and which elevator shaft is provided with a horizontally movable closure gate 11. Said car 8 is provided with a power-controlling lever 12 which extends upward within said car through a slot in the floor thereof. All of the above parts are of well known and standard construction, the opening movement of the gate being in the direction of the arrow marked on Fig. 1.

A forked rocker 13 is pivoted at 14 to and between a pair of laterally spaced plates 15 rigidly secured to the building floor 10 at one side of the gate 11 and just rearward thereof, when said gate is closed. This rocker 13 is arranged to swing in the direction of the movement of the gate 11, and its prongs are indicated by the numerals 16 and 17. The rocker 13 is arranged to receive between its prongs 16 and 17, when the gate 11 is closed, a roller 18 mounted on the rear vertical edge of said gate.

To lock the rocker 13 in a position to hold the gate 11 closed, I provide a latch in the form of a vertically disposed dog 19 intermediately pivoted at 20 to a rearwardly extended arm 21 on the prongs 16 of the rocker 13. Formed with the lower end of the lock dog 19 is a tooth 22 arranged to interlock, under the action of gravity, with any one of a plurality of teeth formed in the rear edge 23 of a vertically disposed ratchet bar 23 mounted between the plates 15 and rigidly secured thereto. Also mounted between the plates 15 and rigidly secured thereto is a

bar-like abutment 24 which is rearwardly spaced from the ratchet bar 23 and between which abutment and ratchet bar the lock dog 19 is free to move both vertically and horizontally. When the gate 11 is closed, the tooth 22 of the lock dog 19 is interlocked with one of the teeth of the ratchet bar 23, as shown in Fig. 1, which in turn holds the rocker 13 locked to prevent the gate 11 from being opened.

To operate the lock dog 19 and thereby release the same from the ratchet bar 23 and permit the gate 11 to open, when the floor of the elevator car 8 is either flush with the building floor 10 or within a predetermined distance above or below the same, I provide an upright cam bar 25 arranged to engage a laterally offset striking surface on the upper end of the lock dog 19 which, as shown, is in the form of a roller-equipped stud 26. Said cam bar 25 is provided with upper and lower end extensions 27 and 28, respectively, that are rearwardly inclined to guide the roller-equipped stud 26 onto said cam bar. Between the lower end of the cam bar 25 and its extension 28 is a rearwardly offset cam surface 29 which extends parallel to the cam bar 25 and provided for a purpose which will presently appear.

The cam bar 25 is held upright for parallel horizontal adjustment by upper and lower bell cranks 30 pivoted to a bearing block 31 secured to the elevator car 8 on the outside thereof. The depending vertical arms of the bell cranks 30 are pivoted to a pair of horizontal lugs 32 rigidly secured to the back of the cam bar 25. The horizontal arms of the bell cranks 30 are pivoted to an upright link 33 which, in turn, is connected to a head 34 by a rod 35 in the form of an eye-bolt, the head of which is pivoted to the upper end of said link. At its upper end the rod 35 extends through a laterally offset sleeve bearing 36 on the lower end of the head 34 and is held therein by a nut 37. A coiled spring 38 encircling the rod 35 is compressed between the lower end of the sleeve bearing 36, and a nut 39, having screw-threaded engagement with said rod. This spring 38 will yield and permit the rod 35 to move upward through the sleeve bearing 36 in case the cam bar 25 is moved while the head 34 is held, as will presently appear. By adjusting the nut 39 on the rod 35, the tension of the spring 38 may be varied, at will.

The head 34 is located on the inside of the elevator car 8 and is secured thereto with freedom for vertical movement by a nut equipped bolt 40 which is secured in the wall of said elevator car and extends through a slot 41 in the head 34. Said head 34 is held against pivotal movement on the bolt 40 by its sleeve-like bearing 36 which extends through a vertical slot 42 in the wall of the

elevator car 8 with freedom for vertical movement therein.

Formed with the head 34 is a pair of oppositely extended wing-like extensions 43, which project in the plane thereof and have formed therein an angular slot 44, the upper edge of which affords two cam surfaces 45, and the lower edges of which afford two cam surfaces 46. These cam surfaces 45 and also the cam surfaces 46 downwardly diverge from the operating lever 12 when in neutral position. A roller-equipped stud 47 is secured to the operating lever 12 and extends into the slot 44 for engagement with the cam surfaces 45 and 46 under the action of said lever.

When the operating lever 12 is in neutral position, its roller-equipped stud 47 is midway between the two cam surfaces 45, and the head 34 is supported thereon. In this position of the head 34, the cam bar 25 is positioned to engage the roller-equipped stud 26 and thereby release the lock dog 19 from the ratchet bar 23, when the elevator car 8 is positioned with its floor substantially in a line with the building floor. Formed in the head 34 below the slot 44 midway between the two cam surfaces 46, is a lock notch 48, adapted to receive the roller-equipped stud 47, when the head 34 is raised, as will presently appear, to lock the lever 12 in neutral position. A depending lug 49 on the rocker 13 is arranged to engage a transverse pin 50 secured to and between the plates 15 and thereby limit the movement of said rocker 13 during the closing of the gate 11.

In Fig. 1, the gate 11 is closed and the car 8 is shown in a stopped position with its floor just above the building floor 10. A slight downward movement of the car will cause the cam bar 25 to engage the roller-equipped stud 26 and thereby release the lock dog 19 from the abutment 23 and move the lower end of said lock dog in engagement with the abutment 24. If the car is stopped with its floor flush with the building floor 10, the roller-equipped stud 26 will be midway between the ends of the cam bar 25. The length of the cam bar 25 limits the distance at which the floor of the car can be above or below the building floor 10 and is still in a position to release the lock dog 19. With the lock dog 19 released, the gate 11 may be moved into an open position and its initial opening movement will cause the roller 18 to swing the rocker 13 rearward and, as the lower end of the lock dog 19 is in engagement with the abutment 24, said abutment acts as a fulcrum therefor and causes the roller-equipped stud 26 to move the cam bar 25 rearward and thereby, through the bell cranks 30, lift the head 34 to carry its lock notch 48 into a position to receive the roller-equipped stud 47 and thereby lock the operating lever 12

in neutral position. Before the roller 18 has moved the rocker 13 into a position in which it will move out of engagement therewith, the pivotal connection between said 5 rocker and the lock dog 19 will have been moved beyond a dead center, and as the cam bar 25 imparts a direct pressure on the roller-equipped stud 26 toward the gate 11, the lock dog 19 and rocker 13 will be securely 10 held by the cam bar 25 in an inoperative position.

During the closing movement of the gate 11, its roller 18 will engage the prong 17 of the rocker 13 and thereby move said rocker 15 in the direction of the closing movement of the gate, which will lift the lock dog 19 and hold the same, as indicated in Fig. 3. When the operating lever 12 is moved in either direction from its neutral position to start the 20 car, its roller-equipped stud 47 will engage the respective cam surface 45 and thereby lift the head 34 which, in turn, through the rod 35, link 33 and bell cranks 30, retract the cam bar 25, release the lock dog 19 and permit 25 the same to be moved by gravity into interlocking engagement with the ratchet bar 23 to again lock the gate 11. As there is a multiplicity of teeth in the ratchet bar 23, the lock dog 19 will be held thereby in 30 different closed positions of the gate 11. When the operating lever 12 is moved into neutral position to stop the car 8, the head 34 and parts carried thereby, including the cam bar 25, will move downward under the 35 action of gravity to position said cam bar to release the lock dog 19, but in case they should stick, the roller-equipped stud 47 will engage the respective cam surface 46 and thereby positively force said parts downward.

In case the car 8 is stopped with the roller-equipped stud 26 in engagement with the lower end of the cam bar 25, said roller-equipped stud, during the movement of the 40 rocker 13 as the gate 11 is opened, will be moved downward out of engagement with said cam bar, which will release said cam bar and thereby permit the head 34 to move downward and release the roller-equipped 45 stud 47 from the lock notch 48, which in turn releases the operating lever 12 were it not for the cam surface 29 onto which said roller-equipped stud moves from the cam bar 25, and thereby continues to hold 50 the operating lever 12 in neutral position.

The purpose of the spring 38 is to yield and permit the rod 35 to move upward through the sleeve bearing 36 and permit an extreme receding movement of the cam bar 55 25, in case the same engages the roller-equipped stud 26 on the lock dog 19 when the gate 11 is open and the car moved while making repairs on the elevator or inspecting the same. This extreme movement of 60 the cam bar 25 is required for the reason

that the head 34 would be held by the roller-equipped stud 47.

The elements 8' and 47', inclusive, and 49' and 50' are identical with the elements 8 to 47, inclusive, and 49 and 50, in Figs. 70 1 and 2, and they function in the same manner, with the single exception that the lock notch 48 is dispensed with. In this form of the invention, I provide means for automatically moving the operating lever 12' 75 from neutral position to offset any tendency of the car 8' to move, due to a leaky valve or leakage around a piston. Said means includes a toothed upright bar 51 and a co-operating horizontal swinging lock blade 80 52, the former of which is slidably mounted in a guide 53 secured to the outside of the car 8', and the latter of which is pivoted at 54 to the building floor 10'. A guard 55, secured to the building floor 10' and overlying the lock blade 52 where it engages the toothed bar 51, holds said lock blade 85 against lifting movement from the floor 10'. The free end of the lock blade 52 is connected to the rocker 13' below its pivot 90 14' by a connecting rod 56. When the gate 11 is closed, the connecting rod 56 holds the lock blade 52 released from the toothed bar 51.

A lever 57 is intermediately fulcrumed to 95 a bracket 58, on the under side of the floor of car 8', and its long end is connected to the lower end of the toothed bar 51 by a link 59. On the short end of the lever 57 is a sliding counter-weight 60. The lever 100 57 is also connected to the operating lever 12' by an arm 61 movable with said operating lever and adjustably attached by a link 62 to the intermediate portion of the long end of the lever 57.

When the gate 11' is moved to open position from its closed position in Fig. 3, the movement of the rocker 13', through the connecting rod 56, will carry the lock blade 110 52 into interlocking engagement with the toothed bar 51. In case the car 8' should move, when the gate 11' is open, the lever 57, which is held by the lock blade 52, toothed bar 51 and link 59 will, through the arm 61 and link 62, move the operating 115 lever 12' into a position to cause the car 8' to move in a reverse direction from which it is being moved by the leakage at the valve or piston.

Referring now to the construction illustrated in Figs. 5, 6 and 7, the elements 8^a to 33^a, inclusive, are identical with the elements 8 to 33, inclusive, and they function in a like manner, but in place of being applied to a hydraulic elevator, they are applied to an electric elevator, having a controlling or switch-acting lever 64 pivoted to a housing 65, which, in turn, is secured to the elevator 8^a. Within the housing 65 are secured contacts 66 with which the lever 120 125 130

64 progressively engages, when moved, either to the left or right from a neutral position, to complete the electric circuit and thereby start the elevator. Leading from the contacts 66 are wires 67 placed in a conduit not shown, which extends from the floor of the car 8^a to the housing 65.

10 A rectangular head 69 is connected to the link 33^a by a rod 70, the lower end of which is pivoted to said link and the upper end of which extends through an offset sleeve 71 on the lower end of the head 69 and is adjustably secured thereto by opposing nuts 72. The head 69 is secured to the elevator 15 3^a by a nut-equipped bolt 73 anchored to said elevator and extended through a vertical slot 74 and in an extension on the upper end of said head. The offset sleeve 71 extends through a slot 75 in the elevator 20 8^a with freedom for vertical movement and holds the head 69 against pivotal movement on the bolt 73. A roller-equipped stud 76 is secured to the switch lever 64, off center from its pivot, and extends into the rectangular head 69 and supports the same when in neutral position, as shown in Fig. 5.

30 Formed in the lower end of the head 69 is a lock notch 77 arranged to receive a stud 76' on the head 69 when the gate 11^a is open and the head 69 raised by the engagement of the cam bar 25^a with the roller-equipped stud 26^a, to lock the switch lever 64 in neutral position. As the roller-equipped stud 76 is off center, a movement 35 of the switch lever 64, either to the left or to the right, to start the car 8^a, will cause said roller-equipped stud to lift the head 69 and thereby move the cam bar 25^a into an inoperative position so that it will pass the roller-equipped stud 26^a without unlatching the lock for the elevator gate 11^a.

40 As a further safeguard to prevent the car 8^a from being moved when the gate 11^a is open, I provide a normally closed secondary switch. This switch comprises a pair of fixed contacts 78 and a co-operating segmental contact 79 normally engaging said two fixed contacts. The fixed contacts 78 are interposed in one of the lead wires 67, secured to the car 8^a and insulated therefrom. The movable contact 78 is mounted on an insulating disc 80 pivoted to the car 8^a and having an arm 81 connected to the rod 70 by a clamp 82. This arm 81 and clamp 82 are connected by a slot and pin connection 83. The arrangement of the movable contact 79 is such that, when the rod 70 is raised by the engagement of the cam bar 25^a with the roller-equipped stud 26^a, the disc 80 is oscillated and thereby moves the movable contact 79 out of engagement with one of the fixed contacts 78 and breaks the circuit. When the gate is closed, the head 69 drops, under the action of gravity, and thereby releases the stud 76' from the lock

notch 77 to permit the switch lever 64 to be operated, and, at the same time, the downward movement of the rod 70 oscillates the disc 80 and again completes the circuit between the fixed contacts 78.

70 What I claim is:

1. In a lock of the kind described, the combination with an elevator car having an operating lever and a shaft closure gate, of a rocker operated by a movement of the gate, a vibratory latch carried by the rocker and normally holding the same to lock the gate closed, and means carried by the elevator car for releasing the latch when the operating lever is moved to neutral position to permit the gate to be opened.

2. The structure defined in claim 1 in which said means locks the operating lever in neutral position when the gate is open.

3. The structure defined in claim 1 in which the latch in turn operates said means to lock the operating lever in neutral position when the gate is open.

4. In a lock of the kind described, the combination with an elevator car having an operating lever and a shaft closure gate, of a rocker operated by the movement of the gate, a latch pivoted to the rocker and normally holding the same to lock the gate closed, and means carried by the elevator car for releasing the latch when said operating lever is moved to neutral position to permit the gate to be opened, the movement of the rocker during the opening movement of the gate being such as to carry the pivot of the latch beyond a dead center.

5. The structure defined in claim 4 in which said means tends to move the latch with its pivot beyond a dead center.

6. In a lock of the kind described, the combination with an elevator car having an operating lever and a shaft closure gate, of a rocker operated by the movement of the gate, a lock dog pivoted to the rocker, a ratchet with which the lock dog normally engages to hold the rocker in a position to lock the gate closed, and means carried by the elevator car for releasing the lock dog from the ratchet when the operating lever is moved to neutral position to permit the gate to be opened.

7. The structure defined in claim 6 in which the latch when moved to a released position in turn operates said means to lock the operating lever in neutral position when the gate is open.

8. In a lock of the kind described, the combination with an elevator car having an operating lever and a shaft closure gate, of a rocker operated by the movement of the gate, a ratchet, an abutment, a lock dog pivoted to the rocker and working between the ratchet and abutment, said lock dog normally engaging the ratchet to hold the rocker in a position to lock the gate closed, and means carried by

the elevator car for releasing the lock dog from the ratchet when the operating lever is moved to neutral position to permit the gate to be opened, said lock dog when moved to a releasing position engaging the abutment and in turn operating said means to lock the operating lever in neutral position when the gate is open.

9. In a lock of the kind described, the combination with an elevator car having an operating lever and a shaft closure gate, of a rocker operated by the movement of the gate, a ratchet, a lock dog having an offset striking surface, said lock dog being pivoted to the rocker and normally engaging the ratchet to hold the rocker in a position to lock the gate closed, a cam bar carried by the elevator car, and means for actuating the cam bar from the operating lever to position the same for engagement with the striking surface of the lock dog to release said lock dog from the ratchet when the operating lever is moved to neutral position.

10. The structure defined in claim 9 in which the cam bar is arranged to engage the striking surface on the lock dog in predetermined positions of the floor of the elevator car above or below the level of the building floor.

11. In a lock of the kind described, the combination with an elevator car having an operating lever and a shaft closure gate, of a rocker operated by the movement of the gate, a ratchet, an abutment, a lock dog having an offset striking surface, said lock dog being pivoted to the rocker, working between the ratchet and the abutment and normally engaging the ratchet to hold the rocker in position to lock the gate closed, a cam bar carried by the elevator car, and means for actuating the cam bar from the operating lever to position the same for engagement with the striking surface of the lock dog to release the same from the ratchet when the operating lever is moved to a neutral position, said lock dog when moved to a releasing position engaging the abutment and in turn operating the cam bar to cause said means to lock the operating lever in neutral position.

12. The structure defined in claim 11 in which the cam bar is arranged to engage the striking surface on the lock dog in predetermined positions of the floor of the elevator car above or below the level of the building floor.

13. The structure defined in claim 12 in which the cam bar is provided with an offset for engagement with the striking surface on the lock dog, in case said striking surface is moved out of engagement with the cam bar when the gate is open, to cause said means to continue to hold the operating lever in neutral position.

14. In a lock of the kind described, the

combination with an elevator car having an operating lever and a shaft closure gate, of a rocker operated by the movement of the gate, a latch normally holding the rocker to lock the gate closed, operating devices including a head having a lock notch and reversely extended cam surfaces, a cam bar carried by the elevator car, said operating devices when the operating lever is in neutral position being arranged to hold the cam bar in position to release the latch and permit the gate to be opened, and a stud on the operating lever for engagement with the cam surfaces on the head when the operating lever is moved to start the elevator car to move the cam bar into an inoperative position, said lock notch being arranged to receive the stud on the operating lever when in a neutral position by a movement imparted to the cam bar from the latch when in a released position.

15. The structure defined in claim 14 in which said operating devices are provided with a yielding section to permit the cam bar to be moved into an inoperative position when the operating lever is held locked in a neutral position.

16. In a lock of the kind described, the combination with an elevator car having a main switch and a normally closed secondary switch and a shaft closure gate, of a rocker operated by the movement of the gate, a latch normally holding the rocker to lock the gate closed, and means carried by the elevator car for releasing the latch, when the main switch is moved to neutral position to permit the gate to be opened and for opening the secondary switch by the opening movement of the gate.

17. The structure defined in claim 1 in further combination with a stop for limiting the releasing movement of the latch, and which means is operated by the latch when held by the stop to lock the lever in neutral position.

18. The structure defined in claim 1 in which said means includes a cam bar having an offset for engagement with the latch, in case said latch is moved out of engagement with the cam bar, when the gate is open, to cause said means to continue to hold the operating lever in neutral position.

19. In a lock of the kind described, the combination with an elevator car having an operating lever and a shaft closure gate, of a rocker operated by a movement of the gate, a vibratory lock dog carried by the rocker, a ratchet normally engaged by the lock dog to lock the gate closed, and means carried by the elevator car for releasing the lock dog when the operating lever is moved to neutral position to permit the gate to be opened.

20. The structure defined in claim 19 in further combination with a stop for limiting

the releasing movement of the rocker, and which means is operated by the latch when held by the stop to lock the lever in neutral position.

- 5 21. In a lock of the kind described, the combination with an elevator car having an operating lever and a shaft closure gate, of a rocker operated by a movement of the gate, a latch normally holding the rocker to lock 15 the gate closed, means including a cam bar carried by the elevator car for releasing the 20

latch when the operating lever is moved to neutral position to permit the gate to be opened, said means being operative to lock the operating lever in neutral position when the gate is open, said means having a yielding section which permits the cam bar to be moved to an inoperative position while the operating lever is locked in a neutral position.

In testimony whereof I affix my signature.

EDWIN CARLSON.
